CLAIM

I claim the ornamental design for a cremation urn and display, as shown and described.

DESCRIPTION

FIG. 1 is a front view of a first embodiment of a bilaterally symmetrical cremation urn and display showing my new design.

FIG. 2 is a right side elevation thereof, the left side being a mirror image;

FIG. 3 is a back side elevation thereof;

FIG. 4 is top plan view thereof;

FIG. 5 is a front view of a second embodiment of a bilaterally symmetrical cremation urn and display showing my new design;

FIG. 6 is a right side elevation thereof, the left side being a mirror image;

FIG. 7 is a back side elevation thereof; and,

FIG. 8 is a top plan view thereof.

The cremation urn and display is shown with a symbolic break in its length. The appearance of any portion of the article between the break lines forms no part of the claimed design. Textual indicia showing numbers or letters are for purposes of environmental illustration and form no part of the claimed design. Dashed or broken lines showing form no part pf the claimed design.
